UNITED STATES PATENT OFFICE.

FRANK P. D'ARCY, OF KALAMAZOO, MICHIGAN.

DESIGN FOR A SPOON.

SPECIFICATION forming part of Design No. 22,029, dated December 6, 1892.

Application filed October 19, 1892. Serial No. 449,403. Term of patent 3½ years.

To all whom it may concern:

Be it known that I, FRANK P. D'ARCY, a citizen of the United States, residing at Kalamazoo, in the county of Kalamazoo and State 5 of Michigan, have invented and produced a new and original Design for a Spoon; and I do hereby declare the following to be a full, clear, and exact description of the same, reference being had to the accompanying drawing, forming a part thereof.

The figure is a top plan view of the spoon.

The object of my invention is to provide a souvenir spoon typical or representative of the city of Kalamazoo, in the State of Michigan.

15 The drawing represents a spoon having my design, which consists of the bowl, the handle of which at the point of its juncture is flat and thence for about one-third of its length is given a spiral twist, and thence for an 20 equal distance the handle is flat, thereby pro-

viding space for a name or any desired inscription, the whole terminating in a representation of a bunch or stalk of celery, which forms the outer and wide end of the handle, the outlines of the leaves forming the margin 25 of the handle, which tapers outwardly from its shank to its top. The leading feature is the end of the handle formed to represent a bunch of celery in combination with the upper and lower flat portion and the intervening 30 twisted portion of said handle.

What I claim is—

The design for a spoon, substantially as herein shown and described.

In testimony whereof I affix my signature in 35 presence of two witnesses.

FRANK P. D'ARCY.
